(57) **CLAIM**

The ornamental design for a casing for a portable light, as shown and described.

DESCRIPTION

FIG. 1 is a front perspective view of our new design of a casing for a portable light;

FIG. 2 is front view of the design of FIG. 1;

FIG. 3 is a back view of the design of FIG. 1;

FIG. 4 is a left side view of the design of FIG. 1;

FIG. 5 is a right side view of the design of FIG. 1;

FIG. 6 is a top view of the design of FIG. 1; and,

FIG. 7 is a bottom view of the design of FIG. 1.

The broken lines in FIGS. 1 through 7 are for illustrative purposes only and form no part of the claimed design.
